UNITED STATES PATENT OFFICE.

WILLIAM C. BOOTS, OF ATTLEBORO, MASSACHUSETTS, ASSIGNOR TO GUYOT BROTHERS,
OF ATTLEBORO, MASSACHUSETTS.

EXPANSIBLE LINK BRACELET.

Application filed April 7, 1926. Serial No. 100,370.

This invention relates to certain new and useful improvements in expandable link bracelets and the primary object thereof is to provide improved means for effecting 5 variation in the length of the same.

A further object of the invention is to provide a device of this character which can be applied to either the central portion of the bracelet or to one of the end links 10 thereof.

The invention still further aims to provide a device of this character which can be easily and quickly operated to effect length variation of the bracelet and which is 15 positive and certain in its holding action.

In the drawings:—

Figure 1 is a bottom plan view of the invention applied to the central portion of a bracelet.

20 Figure 2 is a like view showing the parts separated.

Figure 3 is a section on line 3—3 of Fig. 1.

Figure 4 is a top plan view of one end 25 thereof.

Figure 5 is an end view of the connecting member.

In proceeding in accordance with the present invention, a connecting member is employed, composed of a casing or face plate 1, having side flanges 2, the central parts of which are provided with integral fingers 3, the structure being preferably made of a single blank which is shaped into the form disclosed. A plate 4 is formed with a pair of spaced hollow ribs 5 on each side thereof by bending or curling the side edges of the plate inwardly. The plate 4 is spaced from the face plate 1 and the fingers 3 are bent or curled inwardly to occupy the spaces between the ribs as shown more clearly in Fig. 2 of the drawings. In this way the plate 4 is secured to the face plate 1. The ribs are formed with spaced notches 6 on their outer sides for engagement with lips 7 that extend inwardly from the sides of U-shaped latches 8, the latter being pivoted at 9 to the inner bracelet, the lips being spaced rearwardly of the pivotal points of the latches.

50 The bracelet shown has its ends indicated at B is of the type formed of plates 14 the sides of which are rolled to form double ribs 10 although the invention can be adapted to other types as is evident, and accordingly

the ribs 5 are telescopically received by the 55 ribs 10 and the plates 14 are received in the spaces between the face plate 1 and the plate 4. It will thus be seen that the ribs 5 serve to guide and hold the ribs 10 against lateral movement, while the lips 7 of the latches 60 can be engaged in selected ones of the notches 6 to thus impart the desired length to the bracelet.

In Figure 4 a modified form of the invention is depicted and wherein the connecting member 1' is affixed directly to an outer end 65 of the bracelet, or as shown to the usual hook 1 that engages the bail or loop (not shown) of the wrist watch. In this form of the invention, one of the latches is of course 70 dispensed with and likewise the ribs of the connecting member can be shortened as desired.

Having thus described my invention what I claim as new and desire to secure by Letters Patent is:—

1. In combination with a bracelet of the double rib type having ends, a substantially U-shaped latch pivoted to each of said ends, an inwardly extending lip on each arm of 80 each latch, a connecting member having side flanges and central fingers on the side flanges, and a plate having a pair of spaced hollow ribs on each side thereof disposed between the flanges of the connecting member and receiving the ribs of the bracelet ends thereover, the fingers of the connecting member being bent to lie in said spaces between the hollow ribs, to secure the plate to the connecting member said hollow ribs having a series of notches on their outer sides to 85 selectively receive the lips of the latches.

2. In combination with a bracelet of the double rib type having ends, a substantially U-shaped latch pivoted to each of said ends, 90 lips on the arms of the latches, a connecting member, a plate having notched ribs that are telescopically engaged with the ribs of the bracelet ends, and means to secure the plate to the connecting member, the lips of the latch arms being received in selected 95 ones of the notches.

3. In combination with a bracelet having ends, a connecting member interposed between said ends, means carried by said connecting member to telescopically engage each of the bracelet ends, and means carried by the bracelet ends to latch the latter to 100 105

said first named means, said first named means having a series of spaced keepers to engage said latching means.

4. In combination with a bracelet having attaching means on its ends, a connecting member, means on the connecting member for engaging and holding said attaching means against lateral movement, one of said means being hollow to telescopically receive the other, means carried by one of said means to adjustably latch same to the other, and means carried by the said other means to engage the latching means.

5. In combination with a bracelet end, a member having a pair of means to engage said end, each of the means having a series of notches, and a U-shaped latch pivoted to the bracelet end having lips on each of its arms to engage in selected ones of the notches, the lips being spaced rearwardly of the pivotal point of the latch.

6. In combination with a bracelet having ends provided with hollow portions, a connecting member, means on the connecting member to engage within the hollow portions of the bracelet ends to hold the latter

against lateral movement, securing means on the bracelet ends to adjustably secure the latter to the first named means, and means on the first named means to engage the securing means. 30

7. In combination with a bracelet end, a member having means to engage said end, said means having a series of notches on each side thereof, and a latch pivoted on the bracelet end having lips disposed rearwardly of the pivotal point of the latch and formed to engage in selected notches on each side of the first named means. 35

8. In combination with a bracelet end, a member having means to engage said end, said means having a series of notches on each side thereof, and a U-shaped latch pivoted at its free ends to the sides of the bracelet end and having a pair of inwardly extending lips formed to engage in selected notches on each side of the first named means. 40

In testimony whereof I have signed my name to this specification.

WILLIAM C. BOOTS.
